UNITED STATES PATENT OFFICE.

CARL W. BIESER, OF CINCINNATI, OHIO, ASSIGNEE TO THE GRUEN NATIONAL WATCH CASE COMPANY, OF CINCINNATI, OHIO, A CORPORATION OF OHIO.

WATCHCASE AND PROCESS FOR MAKING SAME.

Application filed April 16, 1928. Serial No. 681,787.

To all whom it may concern:

Be it known that I, CARL W. BIESER, a citizen of the United States of America, and a resident of Cincinnati, in the county of Hamilton and State of Ohio, have invented a new and useful Improvement in a Watchcase and Process for Making Same, of which the following is a specification.

It is the practice to provide watch cases, especially wrist watch cases, with small bars upon which straps employed for securing the case upon the wrist, are carried. The bars are carried by lugs extending from the watch case, these lugs being soldered upon the case.

An object of my invention is to provide a watch bezel and back wherein the soldering heretofore necessary for securing lugs thereupon for mounting of wrist straps and the like is eliminated.

Another object of my invention is to provide a watch bezel having lugs for receiving strap bars, the lugs being formed integral with the back or bezel.

Another object of my invention is to provide a simple, expeditious, and efficient process for forming lugs and watch cases in a single integral structure.

These and other objects are attained by the means described herein and disclosed in the accompanying drawings, in which:

Fig. 1 is a plan view of a forming die, forming a detail of my invention.

Fig. 2 is an inverted plan view of a forming die complementary to that shown in Fig. 1.

Fig. 3 is a fragmental sectional view through the forming die shown in Figs. 1 and 2, taken on lines 3—3.

Fig. 4 is a perspective view of a back embodying my invention and made in accordance with the process embodying my invention.

A blank from which the back or bezel is made is of a form substantially identical with the outline 6 of the recess 7 formed in the plate 14 carried by the die 8, see Fig. 1. The die 8 is mounted on a suitable base 9 carrying a post 10. A sliding block 11 is detachably mounted upon the post 10 and carries the complementary die 12. The

blank is placed in the recess 7 and lies upon the upper face 13 of the die 8. The plate 14 is removably mounted upon the die 8 by suitable means such as screws 15. A way 16 extends through the die 8 and the moving die 12 moves the blank from the recess 7 into the way 16, the side walls 30 of the way serving in co-operation with the moving die 12 to form the perpendicular sides 17 and 18 upon the blank. The further movement of the die 12 carries the blank into the lower extension 19 of the recess and the engagement of the walls 20 and 21 of the recess 19 on the ends of the blank form the upwardly extending flanges 22 and 23 upon the ends of the blank. Pockets 24 are formed in the die 8 into which the blank is carried by the lugs 25 formed on the moving die 12, whereby to form lugs 26 upon the casing or back 5.

By drawing the sheet stock along the side walls of the way 16 whereby to develop the sides 17 and 18 prior to the formation of the flanges 22 and 23 and lugs 26, perfect work is attained, the sides being devoid of wrinkles or breaks. When the ends 22 and 23 are then formed, the material that is precluded from wrinkling or breaking is developed into the lug 26, such lug being formed integral with the walls, ends and base 27 of the casing. The casings made as disclosed herein are lighter in weight than would be the case if solid lugs were soldered upon the casing, and besides a great saving of valuable metal is accomplished. Further, this method eliminates the line of soldering that is noticeable at the place of mounting of soldered lugs upon the casing; especially is this noticeable when white gold is used. Also tremendous savings of time and labor are accomplished.

What I claim is:

1. As a new article of manufacture a sheet metal watch case stamping comprising a base and peripheral flanges extending from the base and integral lugs formed at the periphery, connecting the flanges and lying wholly outwardly beyond one pair of opposite flanges.

2. As a new article of manufacture a sheet metal wrist watch case stamping comprising

ing a base and peripheral flanges extending perpendicular from the base, and lugs connecting adjacent flanges and having opposed parallel faces, one of said parallel faces of each lug being aligned with one face of an adjacent peripheral flange, the lugs being disposed in pairs at opposite ends of the

case and each pair adapted to receive a mounting for wrist straps.

In testimony whereof, I have hereunto ¹⁰ subscribed my name this 9th day of April, 1923.

CARL W. BIESER.
